DESIGN FOR A VENDING MACHINE

Arden A. Bradt, Niagara Falls, N. Y.

Application August 12, 1940, Serial No. 94,376

Term of patent 7 years

To all whom it may concern:

Be it known that I, Ardon A. Bradt, a citizen of the United States, residing at Niagara Falls, in the county of Niagara and State of New York, have invented a new, original, and ornamental Design for a Vending Machine, of which the following is a specification, reference being had to the accompanying drawing, forming part thereof.

The figure is a perspective view of a vending machine, showing the front and one side of my new design, the other side of the design being substantially the same as the one illustrated.

I claim:

The ornamental design for a vending machine, as shown and described.

ARDON A. BRADT.
